US00D794348S

(12) **United States Design Patent** (10) Patent No.: **US D794,348 S**
(45) Date of Patent: **** Aug. 15, 2017**

(54) **SEAT**

(71) Applicant: **ROSET SAS**, Briord (FR)

(72) Inventor: **Philippe Nigro**, Milan (IT)

(**) Term: **15 Years**

(21) Appl. No.: **35/501,179**

(22) Filed: **Jun. 23, 2016**

(80) **Hague Agreement Data**

Int. Filing Date: **Jun. 23, 2016**

Int. Reg. No.: **DM/091239**

Int. Reg. Date: **Jun. 23, 2016**

Int. Reg. Pub. Date: **Jul. 8, 2016**

(51) **LOC (10) Cl.** **06-01**

(52) **U.S. Cl.**

USPC **D6/371**

(58) **Field of Classification Search**

USPC D6/334, 361, 371, 374, 375, 377, 381
CPC A47C 3/00; A47C 3/12; A47C 3/16; A47C

5/00; A47C 7/00; A47C 7/24
